ATTORNEY

UNITED STATES PATENT OFFICE.

JAMES REILLY, OF BROOKLYN, NEW YORK.

APPARATUS FOR HEATING WATER IN BATHS.

SPECIFICATION forming part of Letters Patent No. 433,490, dated August 5, 1890.

Application filed September 21, 1889. Serial No. 324,636. (No model.)

To all whom it may concern:

Be it known that I, JAMES REILLY, a citizen of the United States, and a resident of Brooklyn, in the county of Kings and State of New York, have invented certain new and useful Improvements in Apparatus for Heating Water in Baths, of which the following is a specification.

The invention relates to improvements in apparatus for heating water in baths and other vessels; and it consists in a water jacket or casing communicating at its opposite ends with the bath and inclosing steam inlet and return pipes, the object being to establish a circulation of the water from the bath through said casing until the action of the steam shall have imparted the desired temperature thereto, after which the steam may be turned off.

The means for carrying the invention into effect are fully described hereinafter, and are illustrated in the accompanying drawings, in which—

Figure 1 is a side elevation of a bath-tub with my invention applied thereto; Fig. 2, a top view, partly in section, of the tub, the apparatus constituting the invention being in section on the dotted line 2 2 of Fig. 1; and Fig. 3, an enlarged vertical section on the dotted line 3 3 of Fig. 2, showing the invention in cross-section with the means of attaching it to the tub.

In the drawings, A designates the bath-tub; B, the water-casing; C, the inlet-pipe for steam, and D the return steam-pipe. The casing B is provided in its side and adjacent to its ends with the openings E F, the flanges G, surrounding said openings, being preferably brazed to the internally and externally threaded sleeves H, carrying the threaded nuts I on their exterior and receiving the ferrules J, through which the water from the tub circulates into and from the casing B. The side of the tub A contains apertures a a, through which the ferrules J are passed from the inner side of the tub when it is desired to screw them into the sleeves H, and the outer ends of said ferrules are provided with flanges K, which have a bearing against the inner surface of the tub. Between the nuts I and the outer surface of the tub are provided flexible washers L for insuring the

formation of a tight joint around the apertures a a.

The casing B is arranged at an oblique angle to the horizontal plane of the tub A, in order to facilitate the circulation of the water from the tub into and from the casing during the use of the invention for heating the bath. The casing B is circular in cross-section and is closed at its ends, the mouth end of the casing being preferably brazed to the exterior surface of the intermediate or return pipe D, as shown in Fig. 2, which projects outward beyond said end of said casing and is closed at its ends, the steam being permitted to escape therefrom through the discharge-pipe N. The outer end of the return-pipe D for steam is brazed to the coupling P, which at its outer end will be connected with a suitable source of steam-supply, and at its inner end is in direct communication with the interior steam-pipe C, which is within and smaller in diameter than the return-pipe D. The inner end of the steam-pipe C is open and delivers the steam into the inner end of the pipe D, whence the steam returns along the outer sides of the pipe C and escapes through the pipe N. The steam-pipes are supported at their inner ends by means of steadyng-pins Q, which maintain the relative positions of said tubes.

In the use of the invention the live steam from some suitable source is admitted to the pipe C, while the water from the tub fills the casing B around the pipe D. The steam passes down the pipe C and returns on the outer side of said pipe and within the pipe D to the escape-pipe N, the effect being that the pipe D, becoming heated, imparts heat to the water in the casing B, and the water becoming heated creates a circulation in the bath toward and from the heating devices. After the water has acquired the desired temperature the steam may be cut off from the pipe C.

I recommend the use of thin copper for the manufacture of the steam-pipes and water-casing hereinbefore described.

What I claim as my invention, and desire to secure by Letters Patent, is—

1. The bath-tub and the elongated cylindrical water-casing B, secured to the side of said tub and communicating therewith.

through the openings E F, located adjacent to the ends of said casing, and apertures *a a* in the side of the tub, combined with means, substantially as described, for securing the 5 casing B to the tub, the steam-inlet pipe D, having the coupling at its outer end and being open at its inner end and extending nearly the entire length of the interior of said water-casing, the steam-return pipe D, inclosing 10 and being of greater diameter than the said pipe C and less in diameter than the water-casing, and the discharge-pipe N, connected with said return-pipe, the whole being constructed and arranged substantially as and 15 for the purposes set forth.

2. The bath-tub and the water-casing B in close relation to the side thereof and having flanged openings E F adjacent to its ends, the sleeves H and flanged ferrules J connect-

ing said casing through its said openings with 20 the interior of the tub, combined with the steam-inlet pipe C, having the coupling at its outer end and being open at its inner end, the steam-return pipe D, inclosing said inlet-pipe and being within the water-casing B, 25 and the discharge-pipe N, connected with said return-pipe, said inlet and return pipes extending nearly the entire length of said water-casing, substantially as and for the purposes set forth.

30
Signed at New York, in the county of New York and State of New York, this 19th day of September, A. D. 1889.

JAMES REILLY.
